UNITED STATES PATENT OFFICE

SANFORD E. MCQUIGG, OF BRACKENRIDGE PENNSYLVANIA, ASSIGNOR TO ALLEGHENY STEEL COMPANY, OF BRACKENRIDGE, PENNSYLVANIA, A CORPORATION OF PENNSYLVANIA

FURNACE CHARGING DEVICE

Application filed January 22, 1930. Serial No. 422,530.

This invention relates to furnace charging devices and more particularly to devices for charging and removing loaded annealing boxes such as now used for sheets and the like.

In the steel and other allied industries, the charging of furnaces, such as where box annealing is carried on, presents many difficulties.

It is now customary to employ a separate rigging for charging or discharging each furnace. But, these riggings have been unsatisfactory from many angles.

Further, such riggings are complicated, and, due to the high temperature encountered, many repairs with frequent replacement of parts are necessary.

An object of this invention is to provide a single device that may be employed to charge any number of furnaces.

Another object is the provision of a charging device that may be controlled and operated by an ordinary overhead traveling crane.

A further object is to provide a charging device whose center of gravity may be controlled to meet varied load demands.

A still further object is to provide an efficient, flexible, and positive furnace charging device that shall be relatively inexpensive both as to cost of maintenance and operation.

These, and other objects which will appear to those skilled in the art, I attain by means of the device described in the specification and illustrated in the drawings accompanying the illustrated portion of the application.

In the drawings:

40 Figure 1 is a side view in elevation of an embodiment of my device while in working position.

Fig. 2 is a top plan view of the embodiment of Fig. 1.

45 Fig. 3 is an enlarged side section view taken along the lines III—III of Fig. 2.

Fig. 4 is an enlarged end sectional view taken along the line IV—IV of Fig. 2.

In the drawings, a preferred form of my 50 invention is shown that includes a charging

device designated in its entirety by 10 and having a bottom portion 20 for pushing in and pulling out a charge of a furnace, and an upper portion 30. The lower portion is movably mounted on the upper portion so that the center of gravity of the lower portion 20 may be shifted to obtain a state of balance or equilibrium under different operating conditions.

Although, for the purposes of illustration, I have shown a particular form of furnace 60 having a charged annealing box 61 mounted on a suitable truck 62 carried by suitable rollers 62', operating over tracks 63, it is to be understood that my invention is not limited to any particular form of furnace installation, as it may be utilized in various industrial applications.

In order that the device 10 may be moved from one position to another for acting upon the charge 61 of a given furnace 60, and in order that the device 10 can be operated for pushing the charge into or pulling it out of the furnace 60, the upper portion 30 is provided with an axle 31 extending transversely of its top face 33. Axle 31 is rigidly mounted in spaced, upwardly extending side frames 34 and is provided with an eccentric, central bearing portion 32 adapted to be engaged by a hook 71 carried by cables C of an overhead traveling crane 70 of standard or well known construction.

In order to facilitate engagement or disengagement of hook 71 and bearing portion 32 of axle 31, upwardly projecting and longitudinally extending guide walls 35 are provided. Each guide wall 35 is rigidly secured to the top face 33 and to the axle 31 in alignment with the groove 32. The walls 35 extend longitudinally of upper portion 31 and at substantially right angles to the axle 31. It will be observed that each guide wall 35 extends in an opposite longitudinal direction to the other; and, that each one is slightly bent outwards in a transverse direction at both ends thereof. The purpose of the last mentioned feature is to facilitate the engagement and disengagement of the hook 71 of the crane 70, when the device 10 is not in use, or in case the crane is to be em-

ployed for other purposes. For initially directing the hook 71, upwardly extending guide posts 36 are provided that are rigidly secured to opposite ends of the upper face 33. In order that device 10 may be effective to push a charging car 62 into furnace 60, or to withdraw the same therefrom, portion 20 is provided with a relatively long tapered arm 21. The arm has a relatively blunt bumper 22 that engages a bumper 64 on car 62 when pushing the car into the furnace, or when device 10 is used to push any object to be moved thereby. Arm 21 is also provided with a hook 23 that extends beyond the bumper portion 22, which is adapted to engage the car (or other object) when it is desired to pull the car out of the furnace.

With certain important points in mind, I have distributed the weight of the lower portion 20 in a particular fashion. Half 24 of the lower portion 20 has a solid mass, while the other half 25 and the extending portion 21 are substantially hollow, having reinforcing ribs 26 producing a cellular structure as seen from Fig. 3. The mass 24 has been given a weight much greater than any contemplated furnace charge, in order that the crane 70 need not actually furnish the entire charging force. In other words, I so distribute the weight of the mass of the device 10, with respect to its center of support, that the device 10 will be in a state of balance when exerting either a pushing or pulling force on an object to be moved, such for example, as the charging car 62 and the load thereon.

By the present arrangement, the crane 70 can be moved parallel to the line of charge towards or away from the furnace thereby changing the position of the point of the 40 hang or suspension with respect to the center of mass of the device 10, so that the force of gravity acting upon device 10 will cause the latter to swing like a pendulum to a new position of rest. If this force upon 45 the device were less than the force required to move a charge into or out of a furnace, the crane, itself, would necessarily be required to supply the force necessary to pull or push a charge. Thus by moving the crane in one 50 direction or another, thereby changing the point of suspension of the pendulum, the action of gravity on the device 10, gives rise to a restorative force which is utilized to pull or push the charge 61.

It will also be noted that the eccentric location of the mass 24 of the device 10 automatically holds the hook 23 in engaging position.

The charging device 10 as above set forth 60 can be built to meet the needs of a given weight of charge and of a given furnace, but in order that a single device can be constructed that by means of minor adjustments may be given characteristics suitable for any 65 situation, or in other words, to provide a

universal, interchangeable device, means has been provided whereby the effectiveness of the arm 20 and the mass 24 can be varied, by changing the center of mass of the lower portion 20 with respect to the point of attachment of upper portion 30 to crank hook 71.

For a given adjustment of portions 20 and 30 of device 10, device 10 will be in a state of balance when pushing or pulling a 75 load requiring a definite force to move the same. However, it often happens that loads must be moved requiring either greater or smaller forces, so that the adjustment referred to above may not suit the new conditions, because device 10 may not be in a state of balance when moving such loads. Therefore, in order that device 10 may be adjusted to suit requirements arising in practice, due to either heavier or lighter duties 80 being imposed thereon, means are provided whereby portions 20 and 30 may be moved relatively to one another to such positions that device 10 will be in a state of balance 85 when it exerts the required force on the object to be moved. Such means will be apparent from the following description of device 10.

Upper portion 30 is provided with a downwardly extending portion 43 of inverted T-shape in section. The T portion may, as shown, be made hollow through its longitudinal central portion. The lower portion 20 is provided with vertically extending side walls W and W₁ having shoulders S 100 and S₁ that overhang the flanges F and F₁ of the T portion 43. Thus it will be apparent that when device 10 is suspended from hook 71, the lower portion 20 will be suspended by its shoulders S, S₁, from the flanges F, F₁ of the T portion 43 of upper portion 30. Thus in effect, a dovetail connection is employed for supporting the lower portion 20 on the upper portion 30.

Since the overhanging shoulders S, S₁ of the lower portion 20 present a relatively large bearing area, and since the lower portion is relatively heavy, it will be apparent that a great force would be required to move portion 20 because of the high frictional 115 force developed between the contacting surfaces of these shoulders and the flanges F, F₁ of T portion 43.

Therefore in order that the center of mass of portion 20 may be shifted with respect to the center of mass of portion 30, with a minimum of effort, means are provided whereby, when device 10 is brought to rest on a floor or other support, upper portion 30 will move downwardly to disengage the contacting faces of overhanging flanges F, F₁ and shoulders S, S₁. To facilitate movement of upper portion 30 when device 10 is at rest on a floor or support, the upper portion is provided with rollers or wheels 39 which are 130

mounted on shafts 40 carried by the upper portion 30. The upper portion 30 is hollowed out as at 38 to make room for wheels 39. Wheels 39 roll on faces 28 formed at the top of upwardly extending walls W and W_1 of lower portion 20. Thus faces 28 form a trackway along which the upper portion 30 may be rolled.

In order that the upper portion 30 may be rolled on wheels 39 over the trackway faces 28, a screw 48 is provided, which is journaled in a block 49 secured to face 44 of the inverted T portion 43, and threaded into a bracket 50 which also is secured to said face 44. Screw 48 extends through a post 46, which is disposed in an opening 29 formed in the lower portion 20, and lock nuts 51 mounted on each side of the post 46. Nuts 51 may be secured to screw 48 by set screws K. Thus, when screw 48 is turned by means of a crank 52, the screw will be stationary with respect to post 46. Such being the case, screw 48 will advance through bracket 50, but since the screw cannot move longitudinally, it being held against longitudinal movement by post 46 and nuts 51, screw 48 will move bracket 50 either away from or towards post 46 depending upon the direction in which crank 52 is turned. Since bracket 50 is secured to the upper portion 30, the upper portion 30 will travel on the rollers or wheels 39 over the trackway surfaces 28 in the same direction as nut 50 travels.

Thus, by turning crank 52, when the device 10 is at rest on a floor or support, the center of gravity of the upper portion 30 may be shifted with respect to the center of gravity of the lower portion 20. The relative location of the center of gravity of portions 20 and 30 may be determined by trial to suit the particular load or loads to be moved in the manner previously described herein.

In order that upper portion 30 may be guided as it is moved back and forth on the lower portion 20, post 46 is provided with a flanged head 4 which is partially embraced by guide flanges 45 secured to face 44 of T portion 43 on each side of the post. Flanges 45, as shown, may be secured to T portion 43 by means of dowel pins P.

The operation of the device is very simple. First, the moment of inertia may be adjusted by the handle 52 to meet the demands of a given charge, furnace, and crane. To do this, it is preferable to rotate the crank handle 52 while the device 10 is resting on its lower portion 20, so that the wheels 39 may engage the upper faces 28 and travel therewith; the manual force is thereby lessened. Secondly, the traveling crane 70 is run up, and its hook 71 is connected to the upper portion 30 of the device 10. Thirdly, the crane cab man moves the crane 70 in a direction normal to the fur-

nace 60 to be charged to carry the device 10 to a position in line therewith and thence, and in a direction parallel to the furnace 60 to engage the truck bumper 64 and push the charge 61 into or out of this furnace 60.

It will be noted that the device 10 can be employed to quickly and efficiently charge or discharge a number of furnaces, say in bank, once the moment of inertia of the lower portion 20 has been suitably adjusted; and, that a crane operator, located in an isolated cab, can, himself, accomplish the charging and discharging of a number of furnaces without exposure to the intense furnace heat.

I have also eliminated the need for a separate and specially designed crane for charging purposes. I generally make use of an ordinary overhead traveling crane, preferably of the type capable of longitudinal as well as transverse movement in order that it can be employed to carry the device from one furnace to another of a bank (generally in a longitudinal direction with respect to the shop) and in order that it can be employed to charge and discharge each furnace (generally in a transverse direction with respect to the shop). Further, the crane can be readily disengaged from the device when the charging and discharging operations have been accomplished, and then can be employed for other shop purposes during final treatment of the charges.

While I have described but one embodiment of my invention, it will be apparent that many changes, modifications, substitutions, additions and omissions, or combination thereof may be made without departing from the spirit and scope of the invention as indicated in the appended claims.

I claim:

1. The combination in a charging device having an upper supporting portion and a lower portion suspended therefrom, of means for varying the position of said upper portion with respect to said lower portion, said means including a post and a screw axle positioned to extend therethrough, brackets extending from one of said portions, said axle co-operating with said brackets, so that the moment of inertia of said lower portion can be changed, said lower portion having an extending arm for pushing and pulling a furnace charge.

2. A furnace charging device having an upper supporting portion and a lower pusher and puller portion, said lower portion being pivotally secured to and suspended from said upper portion and having an arm for pushing a charge into the furnace, the pivot including an adjustable screw means extending therethrough for varying the relative positioning of said upper and lower portions and for pulling the charge out of the furnace, said upper portion including means for removably engaging the hook of an overhead

traveling crane, so that said device can be employed to control the charges of a number of furnaces.

3. A furnace charging device having an upper supporting portion and a lower pusher and puller portion, said lower portion having an arm for pushing a charge into and for pulling the charge out of the furnace, said upper portion including means for removably engaging the hook of an overhead traveling crane, said upper and said lower portions being pivotally connected together, said lower portion having a heavy off-balanced weight, means for varying the relative position of the said upper and lower portions, so that the moment of inertia of the lower portion can be changed and that the force of gravity upon the device will be greater than the force required to move the charge into and out of the furnace.

4. A furnace charging device having an upper supporting portion and a lower charging portion, said upper portion having means disposed thereon for engaging the hook of a traveling crane, said lower portion having an arm for moving a charge into and out of the furnace, the said upper and lower portions being pivotally connected, means for changing the position of said upper portion with respect to said pivot that includes wheels mounted in the lower face of said upper portion, so that said upper portion can be moved along the upper face of said lower portion, said lower portion having downwardly extending guide rails secured thereto for supporting the upper end of said pivot, a screw axle positioned to extend through said pivot and through oppositely positioned supporting brackets rigidly secured to and extending downwardly from said upper portion, one of said supports and bolts disposed on both sides of said pivot being threaded to said axle, so that a rotation of said axle will change the position of said support with respect to said pivot, causing the upper portion to move along the said guide rails and along the upper face of said lower portion.

5. In a furnace charging device, a balanced weight adapted to be suspended from a carrying means, a heavy off-balanced weight suspended from said balanced weight and being provided with a charging arm, said arm and the part of said weight adjacent thereto having a cellular structure, the remainder of said weight having a substantially solid structure for off-setting the first mentioned structure.

6. In a furnace charging device having an upper suspending and supporting portion and a lower charging portion provided with a charging arm, the longer part of said lower portion including the charging arm having a substantially cellular construction, the remainder of said lower portion having a solid structure for balancing the weight of the

longer part of said lower portion, said upper portion consisting of a balanced weight and being adapted to be suspended from a carrying means, said lower portion being suspended from and pivotally connected to said upper portion, so that a given moment of inertia may be produced.

7. In a furnace charging device, a lower portion provided with a charging arm, said arm and the part of said portion adjacent thereto having a ribbed and substantially hollow structure, the remainder of said portion having a substantially solid structure for off-balancing and off-setting the weight of the hollow structure.

8. In a furnace charging device, a lower portion provided with a charging arm, said arm and the part of said portion adjacent thereto having a substantially hollow and suitably reinforced structure, the remainder of said portion having a substantially solid structure for off-setting and off-balancing the weight of the hollow structure, and upper portion adapted to be suspended from a carrying means, said lower portion being movably connected to said upper portion so that the moments of inertia of said upper and lower portions may be combined to produce a charging force.

9. In a furnace charging device, a lower portion provided with a charging arm, said arm and the part of said portion adjacent thereto having a substantially hollow and suitably reinforced structure, the remainder of said portion having a substantially solid structure for off-balancing and off-setting the weight of the hollow structure, an upper portion adapted to be suspended and consisting of a substantially balanced weight, said lower portion being movably connected to and suspended from said upper portion, so that the moment of inertia of said upper and lower portions may be combined to produce a charging force.

10. In a furnace charging device, a lower portion provided with an extending charging arm, said arm and a portion of said device adjacent thereto having a substantially hollow form provided with suitable reinforcing ribs, the remainder of said portion having a substantially solid form so that the latter will off-set the weight of the former, and suspending means for carrying said portion.

11. In a furnace charging device, a lower portion provided with an extending charging arm, said arm and the part of said portion adjacent thereto having a substantially hollow form provided with suitable reinforcing ribs, the remainder of said portion having a suitable solid form so that the latter will off-set the weight of the former, an upper portion consisting of a substantially balanced weight, said upper portion being provided with means for removably engag-

ing a suspending and carrying means, said lower portion being suspended from and pivotally connected to said upper portion, so that the moments of inertia of said portions may be combined to produce the charging force.

12. In a furnace charging device having an upper supporting portion and a lower pusher and puller portion, said lower portion having an arm for pushing a charge into and for pulling the charge out of the furnace, said upper portion including a transversely positioned axle having an eccentric groove cut therein for removably engaging the hook of an overhead traveling crane, said lower portion being pivotally connected to and suspended from said upper portion and means for varying the relative position of said upper and lower portions so that the moment of inertia of the lower portion can be changed.

13. In a furnace charging device having an upper supporting portion and a lower charging portion, said upper portion having means disposed thereon for engaging the hook of a traveling crane, said lower portion having an arm for moving a charge into and out of the furnace, said lower portion being movably connected to and suspended from said upper portion, means for changing the position of said upper portion with respect to said lower portion that includes a screw axle connected to said lower portion positioned to extend through oppositely positioned supporting brackets rigidly secured to and extending downwardly from said upper portion.

14. In a furnace charging device having a lower charging portion and an upper supporting portion provided with a transversely extending axle having an eccentric groove cut therein for receiving the hook of a crane, a pivot means for connecting said upper and lower portions together, and means for varying the relative positioning of said upper and lower portions, said means including a screw axle positioned to extend through said pivot and to cooperate with brackets extending downwardly from the upper supporting portion.

15. In a furnace charging device having an upper supporting portion and a lower charging portion provided with a charging arm, of means for pivotally and variably securing said lower portion to said upper portion, said means including a screw means for moving said lower portion with respect to said upper portion, and also, including wheels rotatably positioned in said supporting portion for moving the upper portion on said lower portion.

16. In a furnace charging device having an upper supporting portion and a lower charging portion, said upper portion having an inverted T-shaped longitudinally extending central portion, said lower portion being

slotted to receive said inverted T-shaped portion, guideways rigidly secured to and extending downwardly from the lower face of said T-shaped portion, and means connecting said upper portion to said lower portion having a T-shaped upper portion cooperating with said guideways, and means for moving said connecting means along said guideways, so that the relative positioning of said upper and lower members may be varied.

17. The combination with an overhead traveling support having a cable and a hook, of a heavy mass suspended from said hook, said mass comprising an upper body portion suspended from the hook, a lower body portion of relatively large mass movably supported by said upper portion, said lower portion having a relatively long puller and pusher arm thereon, and screw mechanism operatively connected to said upper and lower body portions for moving one of said body portions relative to the other, thereby shifting the combined centers of mass of said body portions relative to the point of attachment of the upper body portion to said hook.

In testimony whereof, I have hereunto subscribed my name this 18th day of January, 1930.

SANFORD E. McQUIGG.
